US0D1030087S

(12) **United States Design Patent** (10) **Patent No.:** **US D1,030,087 S**
(45) **Date of Patent:** **** Jun. 4, 2024**

(54) **BIOLOGICAL TESTING APPARATUS**

(71) Applicant: **IVD R.E.D. Microfluidic Chip Service & Support Corp., Hsinchu (TW)**

(72) Inventor: **Ya-Lin Huang, Hsinchu (TW)**

(73) Assignee: **IVD R.E.D. MICROFLUIDIC CHIP SERVICE & SUPPORT CORP., Hsinchu (TW)**

(**) Term: **15 Years**

(21) Appl. No.: **29/842,568**

(22) Filed: **Jun. 14, 2022**

(30) **Foreign Application Priority Data**

Dec. 16, 2021 (TW) 110306867

(51) **LOC (14) Cl.** **24-02**

(52) **U.S. Cl.**

USPC **D24/216**

(57) **CLAIM**

The ornamental design for a biological testing apparatus, as shown and described.

DESCRIPTION

FIG. 1 is a top, front, left perspective view of a biological testing apparatus, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left-side elevation view thereof; and,

FIG. 7 is a right-side elevation view thereof.

The broken lines in the drawings depict portions of the biological testing apparatus that form no part of the claimed design.

1 Claim, 5 Drawing Sheets
